UNITED STATES PATENT OFFICE

171,181

BOOK BOX DESK OR SIMILAR ARTICLE

William James Bargen, Waukegan, Ill.

Application April 10, 1953, Serial No. 24,431

Term of patent 14 years

(Cl. D33—11)

To all whom it may concern:

Be it known that I, William James Bargen, a citizen of the United States of America, resident of Waukegan, in the county of Lake and State of Illinois, have invented a new, original, and ornamental Design for a Book Box Desk or Similar Article, of which the following is a specification, reference being had to the accompanying drawing, forming a part thereof.

In the drawings:

I claim:

The ornamental design for a book box desk or similar article, as shown.

WILLIAM JAMES BARGEN.
